UNITED STATES PATENT OFFICE

JABEZ C. NELSON, OF SYRACUSE, NEW YORK

DESIGN FOR A COMBINED WRINGER AND CASING FOR A WASHING MACHINE

Application filed July 30, 1931. Serial No. 40,730. Term of patent 14 years.

To whom it may concern:

Be it known that I, JABEZ C. NELSON, a citizen of the United States, residing in the city of Syracuse, in the county of Onondaga and State of New York, have invented a new, original, and ornamental Design for a Combined Wringer and Casing for a Washing Machine, of which the following is a specification, reference being had to the accompanying drawings, forming part thereof. Figure 1 is a top plan view of a combined

wringer and casing for a washing machine showing my new design;

Figure 2 is a perspective view of the right hand side; and

Figure 3 is a perspective view of the left hand side of the same.

I claim:

The ornamental design for a combined wringer and casing for a washing machine, substantially as shown.

JABEZ C. NELSON.
